DESIGN FOR AN AIRPLANE

Raymond C. Sebold, Fort Worth, Tex., assignor to
Consolidated Vultee Aircraft Corporation, San
Diego, Calif., a corporation of Delaware

Application September 17, 1945, Serial No. 122,123

Term of patent 14 years

(Cl. D71—1)

To all whom it may concern:

Be it known that I, Raymond C. Sebold, a citizen of the United States, residing at Fort Worth, in the county of Tarrant and State of Texas, have invented a new, original, and ornamental Design for an Airplane, of which the following is a specification, reference being had to the accompanying drawings, forming a part thereof.

In the drawings:

Figure 1 is a top plan view of an airplane, showing my new design;

Figure 2 is a front elevational view;

Figure 3 is a side elevational view; and

Figure 4 is a bottom plan view thereof.

I claim:

The ornamental design for an airplane, substantially as shown.

RAYMOND C. SEBOLD.
